DOOR SEAL

Everett H. Galford, Charleston, W. Va.

Application March 19, 1943, Serial No. 479,765

2 Claims. (Cl. 20—68)

My invention relates to doors, and has among its objects and advantages the provision of an improved door seal.

In the accompanying drawing:

Figure 1 is a face view of the bottom end of the conventional door illustrating my invention applied thereto.

Figure 2 is a sectional view along the line 2—2 of Figure 1.

Figure 3 is a fragmentary sectional view of the 10 door in a partly opened position.

Figure 4 is a sectional view along the line 4—4 of Figure 1.

Figure 5 is a sectional view of the bottom end of the door.

Figure 6 is a perspective view of a seal actuating wing, and

Figure 7 is a face view of a guide plate and spring attachment.

In the embodiment of the invention selected for illustration, the door 10 is provided with a groove 12 in its lower end face 14. Inside this groove is mounted a sealing plate 16 having angular slots 18 loosely receiving correspondingly angled wings 20 attached at 22 to the door 10. Recesses 26 are formed in the end face 14 for the ears 28 on the wings 20 to bring the ears flush with the end face of the door. Figure 6 illustrates the ears 28 of that wing 20 spaced so that the sealing plate 16 may move therebetween for engagement with the sill 30. Each ear 28 is provided with an opening for the reception of one of the fastening screws 22.

While the slot 12 is relatively narrow to guide the plate 16 in its vertical movement, the door is cut out at 32 to provide accommodation for the wings 20. Figure 5 illustrates the position of the plate 16 when the door 10 is opened. In this position, the shoulder 34 at one end of the plate engages a stop plate 36 secured to the vertical edge 38 of the door. A slot 40 is provided in the plate 36 for accommodating a projection 42 on the plate 16. A tension spring 44 is connected at one end with the plate 36 and at its other end with the plate 16 to yieldingly hold the latter in the position of Figure 5.

The door frame structure 46 is recessed to receive a plate 48 made secure by screws 50. The plate 48 is located for engagement with the projection 42 as the door 10 is being moved to a closed position. With the door 10 opened, the tension of the spring 44 pulls the sealing plate 16 into engagement with the stop plate 36 and elevates the plate 16 by reason of the angularity of the slots 18 and the wings 20. As the door swings to a closed position, the plate 48 engages

the extension 42 and shifts the sealing plate 16 in the opposite direction to bring its lower edge into engagement with the sill 30 and thereby provide an effective weather seal.

Without further elaboration, the foregoing will so fully illustrate my invention, that others may, by applying current knowledge, readily adapt the same for use under various conditions of service.

I claim:

1. A door provided in its lower edge with a groove, a sealing plate located within said groove and provided with slots inclining upwardly from its lower edge, the groove being slightly wider than the thickness of the sealing plate and provided opposite the slots of the sealing plate with widened portions, wings of greater width than the groove and fitting in said widened portions thereof, the wings being each provided at its lower edge with a pair of spaced ears located at opposite sides of the groove and secured to the lower edge of the door, the wings extending across the groove and arranged at an inclination similar to that of the slots and fitting in the slots to support the sealing plate for downward or upward movement with relation to the lower edge of the door, a slotted stop plate secured to one vertical edge of the door with its slot in registration with one end of the groove, a coil spring secured to the sealing plate and to the stop plate, a shoulder on the sealing plate contacting the stop plate, and a projection on, the sealing plate extending through the slot of the stop plate.
2. A door provided in its lower edge with a groove, a sealing plate located in said groove and provided with slots inclining upwardly from its lower edge, the groove being slightly greater in width than the thickness of the sealing plate, wings located in said groove and extending entirely across the same, the wings being inclined similar to and fitting in said slots to support the sealing plate for angular downward or upward movement with relation to the lower edge of the door, relatively spaced ears on the lower ends of the wings secured to the lower edge of the door, the ears of each wing being located at opposite sides of said groove to permit the passage of the sealing plate between the same, means acting on the sealing plate during the closing of the door to effect the downward movement of the sealing plate, and means acting on the sealing plate during the opening of the door to effect the upward movement of the sealing plate.
